**SUMP-TYPE CONTAINERS FOR TRANSPORTING
AND DUMPING EQUIPMENT**

Harry W. Jones, Knoxville, Tenn., assignor to Dempster Brothers, Inc., Knoxville, Tenn., a corporation of Tennessee

Application December 29, 1952, Serial No. 328,310

15 Claims. (Cl. 298—30)

This invention relates to improvements in sump-type containers, and more particularly to the type of containers used for trash, garbage, and other refuse.

It has been customary to handle refuse containers with transporting and dumping equipment of the types set forth in the patents of George R. Dempster, No. 2,281,183, April 28, 1942, and No. 2,369,722, February 20, 1945, as examples of such equipment. Such containers customarily are filled while sitting on the ground or on the floor, street, etc., and thereafter may be picked up by the transporting and dumping equipment on a motor vehicle, on which the container may be transported to the point of dumping, the contents discharged, and returned or hauled to the point of re-use. Frequently, a considerable quantity of liquid may be received in the container, especially when hauling garbage and other materials, but when the container has a drop bottom as in Patent No. 2,369,722, and is tilted forward on the vehicle in its transport position, the liquid spills out. Furthermore, some of the liquid may leak out at the point of filling and contaminate the spot around the container so as to be highly objectionable in service.

One object of the invention is to retain a considerable quantity of liquid within the container while sitting in its position to be filled, and then later, when the container is raised and tilted forward on the transporting equipment in its carrying position, the liquid is retained in the container without danger of leaking out.

A further object of the invention is to provide in a drop bottom container the provision of a sump at or adjacent the point of connection of the drop bottom door with the body of the container which will receive and enclose the liquid contents thereof and prevent leakage through the crack between the door and container when the container is tilted in carrying position.

Still another object of the invention is to provide for the sealing of the crack between a drop bottom door and the body of a container on which it is used against the leakage of the contents therefrom when the container is tilted in carrying position.

These objects may be accomplished according to one embodiment of the invention by constructing a drop bottom container with a sump therein which normally contains liquid. This sump includes a receptacle provided on the drop bottom door adjacent the point of pivotal connection between the edge of the door and the body of the container which will trap the liquid in the container against leakage when the container is tilted in its carrying position on the vehicle. This provides a leakproof sump with a receptacle of substantial quantity that will allow the container to tip forward to a considerable degree without leakage through the crack between the door and the body of the container. Provision may be made for sealing the crack and shedding the contents of the container when the door is opened, as by the provision of a sealing gasket or flap which overlies the crack therebetween and thus insures proper shedding

of the contents over the door when dropped in open position.

This embodiment of the invention is illustrated in the accompanying drawings, in which:

Fig. 1 is a side elevation of a transporting and dumping unit showing the container in place thereon and tilted;

Fig. 2 is a perspective view showing the container in dumping position;

Fig. 3 is an end elevation of the container detached;

Fig. 4 is a cross section through the hinge portion of the container in open position; and

Fig. 5 is a similar view with the door in closed position.

The invention is shown as applied to transporting and dumping equipment of the character generally represented in the Dempster Patent No. 2,369,722, February 20, 1945, merely as an example of the type of equipment in connection with which it may be used.

This transporting and dumping equipment includes a motor vehicle chassis generally designated by the numeral 20, upon which is mounted a hoisting unit, comprising a sub-frame 2 having a container rest generally indicated at 3 mounted thereon and inclined forwardly of the motor vehicle. Boom arms are shown at 4, pivotally mounted at 5 at their forward ends to the sub-frame 2 and adapted to be raised and lowered by hydraulic hoists 6.

A skid frame is shown at 7 mounted on the sub-frame 2 for bodily movement lengthwise relative thereto between the position shown in Fig. 1 and a forward position in which the container may be lowered onto the rest 3. Suitable means is provided for moving the skid frame 7 forward and rearward of the chassis, as described more fully in the Dempster patents referred to above. The free ends of the boom arms 4 support the container by flexible devices such as chains 8, attached to the boom arms at 9 to raise and lower the container to and from its dumping position. The skid frame 7 is also provided with a dumping hook (not shown) to be engaged with the container for dumping the latter in the position shown in Fig. 2.

The foregoing transporting and dumping equipment, generally as described above, is set forth and disclosed more fully in the Dempster patents referred to, particularly No. 2,369,722.

The container illustrated as an embodiment of this invention, for use with the transporting and dumping equipment is shown in Figs. 1 and 2, and more fully in Figs. 3 to 5. This container is constructed preferably of sheet metal of relatively heavy gauge, according to the size and capacity of the container and the material to be contained therein, but is substantially of rigid unitary structure. End walls are shown at 10; front and back walls at 11 and 12; and a bottom at 13, all being formed of suitable steel plates or the like, rigidly connected together as by welding, or other fastening means.

The bottom 13 is provided with upturned end portions 14 formed rigidly therewith in positions to fit into cutout notches 15 provided in the end walls 10 of the container, and may be made as usual by notching out the end plates, using the cutout portions to form the end sections 14 of the bottom 13.

The bottom 13 is also provided with upwardly inclined forward and rearward edge portions 16 and 17, respectively, which cooperate with the end sections 14 to provide a sump in the drop bottom 13 for containing liquid therein.

The drop bottom 13 is hinged to the forward wall 11 of the container at 18, along the upper edge of the inclined portion 16, as shown more clearly in Figs. 3 to 5. The drop bottom 13 may be lowered about the hinge 18 to the open position shown in Figs. 2 and 4 for dumping the contents of the container.

The hinged connection between the drop bottom 13 and the body of the container leaves a crack therebetween at the hinge edge of the drop bottom door 13. I have provided a deflector plate 19 overlapping this crack in order to shed the contents of the container over the door when the latter is in dumping position as illustrated in Figs. 2 and 4. This deflector plate 19 extends downwardly in an inclined direction from the front wall 11 of the container and throughout the length of the container between the end walls 10 thereof. The deflector plate 19 may be welded at its upper edge to the front wall 11 and may be held in place, as shown, by a brace 20 interposed between the lower edge portion of the plate 19 and the plate of the front wall 11.

This shedding action may be increased by the provision of a resilient sealing means 21 on the lower edge thereof overlapping the crack between the door 13 and the body of the container. In the form illustrated, this sealing means is provided by a resilient or rubber flap 21 which is attached at one edge to the lower edge of the plate 19 in position to be engaged by the adjacent portion of the drop bottom door 13 when the latter is closed. The resilient sealing means may be connected also with the door, if desired, and be in the form of a bellows or other yieldable connection therebetween that will effectively seal the crack.

The hinged edge portion of the drop bottom door 13 is provided also with a receptacle 22 therein adjacent the hinge 18. This receptacle 22 is formed by an upwardly inclined wall portion 23 in cooperation with the inclined edge portion 16 of the door 13, which portion 23 extends throughout the length of the container and has a forwardly turned top portion 24. These receptacle portions 23 and 24 may be provided by plates extending between the upturned portions 14 on the drop bottom door and welded or otherwise secured thereto in sealing relation therewith so as to form a closed receptacle in the hinge edge of the drop bottom door. Braces may be provided at intervals along the length of the receptacle 22 as indicated at 25. The top wall portion 24 is in position to engage or be connected with the sealing member 21 when the door is in its closed position as shown in Fig. 5, whereby to seal the crack therebetween, as well as to insure of proper shedding of the contents when the door is open, as illustrated in Figs. 2 and 4.

Lifting pins are provided at 26 on the end sections 14 of the door 13 for detachably engaging the free ends of the chains 8 to lift the container from its filling position on the ground or other surface onto the skid frame 7 and to hold the container in dumping position, as well as for handling the container generally. The chains 8 extend from the lifting pins 26 over boom rests 27 secured to the end walls 10 of the container at points above the lifting pins 26 and adjacent the front wall 11 so as to insure of proper support of the container by the chains.

As set forth more in detail in the above-mentioned Dempster patents, the skid frame 7 is provided with one or more dumping hooks thereon for engaging the body of the container for dumping. The front wall 11 is shown as provided with an indentation therein, generally indicated at 28, within which is located a cross bail 29 adapted to be engaged by the hook (not shown) on the skid frame 7 to hold the body of the container elevated, as illustrated in Fig. 2, for dumping of the contents upon lowering of the drop bottom 13.

The walls of the container are securely reinforced as usual by ribs or reinforcing members thereon and extending circumferentially around the container. Reinforcing bars are shown also at 30 on the drop bottom door 13, extending lengthwise thereof for bracing the bottom door. One of the reinforcing bars on the bottom, designated 31, has upturned ends 32 intermediate the width of the door immediately beneath the lifting pins 26 and welded securely to the end sections 14.

14 to strengthen the latter at the points where the lifting force is applied. This adds material rigidity to the drop bottom door at these points.

The container may be open at its top or provided with 5 any suitable closure or doors therefor as desired, according to the material to be handled therein and the desirability for enclosing such material.

The container is adapted to be loaded, transported and dumped substantially as set forth more fully in the 10 Dempster patents referred to above, particularly No. 2,369,722. When the container is sitting in its level position on the ground during filling, as illustrated in Fig. 3, the sump provided in the door 13 will contain a considerable quantity of liquid therein, having a liquid level 15 which is at the height of the upper edges of the inclined portions 16 and 17, as indicated at A in Fig. 3. For one size of container, this liquid level will hold 110 gallons of liquid.

When the same container is lifted from its level position, shown in Fig. 3, to a position in which it rests against the skid frame 7, as shown in Fig. 1, it will be noted that the body of the container tilts forward of the vehicle through at least 15½ degrees in its carrying position. Inasmuch as a crack is formed at the point of 20 the hinged connection between the drop bottom door 13 and the body of the container along the front wall 11, the liquid contents would spill out of the container almost entirely in tilting the container to the position shown in Fig. 1, with only a very small quantity of the 25 liquid remaining therein, as diagrammatically illustrated by the dotted line B in Fig. 3. However, by the provision of the receptacle 22 along the hinge edge of the drop bottom door 13, this liquid carrying capacity in the tilted position of the container is raised to the liquid level generally indicated by the dotted line C in Fig. 3. In the example given above as a representative size of container, the liquid level at the point C is 135 gallons capacity, which therefore exceeds the liquid capacity when resting flat on the ground and thereby will retain in the 30 container all of the liquid contents that would be retained when the container is flat in its filling position without spillage of any of the liquid contents in tilting of the container to its carrying position. Thus the receptacle provided on the drop bottom door is more than sufficient 35 in capacity to contain intact all of the liquid that has been retained in the sump portion of the container during filling. Thus, an effective leakproof sump-bottom container is provided that will retain the liquid contents, even when the container is tilted to its carrying position.

The construction provided herein would leave a crack and possibly a ledge at the upper edge of the door in open position, as shown in Figs. 2 and 4. I have provided shedding and sealing means along this portion of the hinge edge of the drop bottom door by a deflector plate 19 and sealing means 21 that overlie the crack of the receptacle 22 to insure of proper shedding of the contents of the container over the open door as the latter hangs down in its open position, substantially as shown in Fig. 2. The rubber, flexible or resilient flap 21 need not necessarily be connected with the receptacle walls 23 and 24, although it may be connected therewith if desired, and thus fold up or telescope in the manner of a bellows during the closing action of the drop bottom door.

65 In this way I have provided an effective leakproof sump that will retain all of the liquid contents of the container even during transporting of the latter in an inclined or tilted position which is highly desirable with containers of this type.

While the invention has been illustrated and described in one embodiment, it is recognized that variations and changes may be made therein without departing from the invention set forth in the claims.

I claim:

1. A container of the character described comprising

front, rear and end walls, and a bottom door hinged to the walls of the container adjacent the front wall, said bottom door having a liquid sump therein, and a receptacle on the bottom door adjacent the hinge and extending in the container above the sump in position to receive therein the liquid in the sump upon forward tilting of the container.

2. A container of the character described comprising front, rear and end walls, and a bottom door hinged to the walls of the container adjacent the front wall, said bottom door having a liquid sump therein, and a receptacle on the bottom door adjacent the hinge on the upper side of the door and extending in the container above the sump with an open side toward the sump in position to receive therein the liquid in the sump upon forward tilting of the container.

3. A container of the character described comprising front, rear and end walls, and a bottom door hinged at the front edge thereof to the front wall of the container, said bottom door having a liquid sump therein, and a receptacle on the hinge edge portion of said bottom door and extending in the container above the sump with an open side toward said sump in position to receive therein the liquid from the sump upon forward tilting of the container.

4. A container of the character described comprising front, rear and end walls, and a bottom door hinged at the front edge thereof to the front wall of the container, said bottom door having a liquid sump therein, and a receptacle on the hinge edge portion of said bottom door and extending along said edge from side edge to side edge thereof and extending in the container above the sump with an open side toward said sump in position to receive therein the liquid from the sump upon forward tilting of the container.

5. A container of the character described comprising front, rear and end walls, and a bottom door hinged at the front edge thereof to the front wall of the container, said bottom door having upturned opposite end portions and upturned front and back edge portions forming a liquid sump therein, and means forming a receptacle on the hinge edge portion of said bottom door and extending in the container above the sump with an open side toward said sump in position to receive therein the liquid from the sump upon forward tilting of the container.

6. A container of the character described comprising front, back and end walls, and a drop bottom door hinged to the lower edge of the front wall, said bottom door having a portion of each end wall connected therewith and having upturned front and rear edge portions cooperating to form a sump in the bottom door, and means forming a receptacle on the upper surface of the door adjacent the hinge edge thereof within the container and above the sump and opening toward the sump in position to receive the liquid therefrom upon forward tilting of the container.

7. A container of the character described comprising front, back and end walls, and a drop bottom door hinged to the lower edge of the front wall, said bottom door having a portion of each end wall connected therewith and having upturned front and rear edge portions cooperating to form a sump in the bottom door, and a receptacle on the upper surface of the door adjacent the hinge edge thereof beside the sump and opening toward the sump in position to receive the liquid therefrom upon forward tilting of the container, said receptacle comprising a wall extending upwardly and rearwardly from the door and from side edge to side edge thereof.

8. A container of the character described comprising front, rear and end walls, and a bottom door hinged at the front edge thereof to the front wall of the container, said bottom door having a liquid sump therein, and a receptacle on the hinge edge portion of said bottom

door and extending in the container above the sump with an open side toward said sump in position to receive therein the liquid from the sump upon forward tilting of the container, and deflector means connected with the front wall in position to engage the receptacle in the closed position of the door and substantially closing the crack between said front wall and the receptacle.

9. A container of the character described comprising front, rear and end walls, and a bottom door hinged at the front edge thereof to the front wall of the container, said bottom door having a liquid sump therein, and a receptacle on the hinge edge portion of said bottom door and extending in the container above the sump with an open side toward said sump in position to receive therein the liquid from the sump upon forward tilting of the container, and a deflector connected with the front wall in position to engage the receptacle in the closed position of the door and overlapping the receptacle substantially closing the crack therebetween.

10. A container of the character described comprising front, rear and end walls, and a bottom door hinged at the front edge thereof to the front wall of the container, said bottom door having a liquid sump therein, and a receptacle on the hinge edge portion of said bottom door and extending in the container above the sump with an open side toward said sump in position to receive therein the liquid from the sump upon forward tilting of the container, a deflector plate connected with the front wall and extending downwardly and rearwardly therefrom, and a flexible flap connected with said deflector plate and extending in overlapping relation with the receptacle in position to engage the receptacle in the closed position of the door to shed material over the door in open position.

11. A container of the character described comprising front, rear and end walls, and a bottom door hinged at the front edge thereof to the front wall of the container, said bottom door having upturned opposite end portions and upturned front and back edge portions forming a liquid sump therein, and a wall secured to the bottom door adjacent the hinged edge thereof and extending upwardly and rearwardly therefrom and substantially throughout the width of the door and cooperating therewith to form a receptacle open in the direction of the sump in position to receive liquid therefrom upon forward tilting of the container.

12. A container of the character described comprising front, rear and end walls, and a bottom door hinged at the front edge thereof to the front wall of the container, said bottom door having upturned opposite end portions and upturned front and back edge portions forming a liquid sump therein, and a wall secured to the upturned front end portion and extending rearwardly therefrom substantially throughout the width of the door between said upturned end portions, said wall cooperating with the door to form a receptacle along said hinge edge open to the sump to receive liquid therefrom upon forward tilting of the container.

13. The combination with a vehicle, of a container, means on the vehicle for supporting the container in a position inclined toward the front of the vehicle, said container having a bottom hinged thereto substantially at the bottom of the front wall thereof, said bottom having a sump formed therein, and means forming a receptacle above the sump and between the sump and the hinge in position to receive the contents of the sump when the container is held by the supporting means in the forwardly inclined position on the vehicle, said receptacle being open in the direction of the sump to receive liquid therefrom upon tilting of the container.

14. The combination with a vehicle, of a container, means on the vehicle for supporting the container in a position inclined toward the front of the vehicle, said container having a bottom hinged thereto substantially at the bottom of the front wall thereof, said bottom hav-

ing a sump formed therein, and a wall extending upwardly from the door and outwardly away from the hinge thereof forming a receptacle along said hinge edge open in the direction of the sump to receive liquid therefrom upon tilting of the container on said supporting means toward the front of the vehicle. 5

15. A container of the character described comprising surrounding walls and a drop bottom door entirely within the confines of the surrounding walls, means hinging the door at one edge thereof to the surrounding wall, said door having a liquid sump therein, and a receptacle extending in the container along the hinge edge of the door and projecting above the sump, said receptacle having an open side toward the sump in position to receive the liquid

therefrom upon tilting movement of the container toward the hinge edge of the door.
